UNITED STATES PATENT OFFICE.

FRANK B. BELL, OF CHICAGO HEIGHTS, ILLINOIS, ASSIGNOR TO EDGEWATER STEEL COMPANY, OF PITTSBURGH, PENNSYLVANIA, A CORPORATION OF PENNSYLVANIA.

ROLLING-MILL.

1,350,057.

Specification of Letters Patent. Patented Aug. 17, 1920.

Application filed August 7, 1915, Serial No. 44,256. Renewed July 9, 1920. Serial No. 395,173.

To all whom it may concern:

Be it known that I, FRANK B. BELL, a citizen of the United States, residing in Chicago Heights, in the county of Cook and State of Illinois, have invented a new and useful Improvement in Rolling-Mills, of which the following is a specification.

This invention relates in general to rolling mills and has more particular reference to rolling mills provided for the rolling of large and heavy metal disk and annular bodies, such as, for example, railway car wheels, tires for railway locomotive wheels, turbine rings, gear rings, crusher shells and the like. Although the invention is herein-after described in connection with the rolling of railway wheels and tires, it will be manifest as the invention is better understood that it has a more general application. A principal object of this invention is the provision of a mill of the character described which may be used with slight and simple adjustment and through the substitution of a minimum number of parts for the rolling of both disk and annular bodies, thereby adapting such a mill for car and locomotive wheels.

A further and decidedly important object of this invention is the provision of a mill which will accurately roll solid steel railway car wheels and which is constructed and arranged to minimize the amount of preliminary work that must be done upon the blanks or blooms before they are placed in the mill.

A further object of the invention is the simplification of the structure of wheel rolling mills and the elimination of all delicate and readily damaged parts.

A further object of the invention is the provision of a rolling mill of the character described which will have a wide range of adjustment, thereby enabling the same mill to be used in the production of articles of general cylindrical form but having widely different thicknesses or lateral widths.

A further object of the invention is the provision of a mill of the character described wherein the operator will have a better control of the mill to produce accurate dimensioning of the articles than has been possible prior to my invention.

Other objects and advantages of the invention will be apparent as it is better understood from the following description when considered in connection with the accompanying drawings which illustrate a present preferred embodiment of my invention and show a mill embodying it arranged for the rolling of both car wheels and locomotive tires.

Referring to the drawings,

Figure 1 is a central sectional view taken through a rolling mill embodying my invention and showing the same arranged for the rolling of locomotive tires;

Fig. 2 is a horizontal section of the same;

Fig. 3 is a view similar to Fig. 1 and showing the mill arranged for the rolling of a railway car wheel;

Fig. 4 is a top plan view of the mill as arranged in Fig. 3 with parts removed to better disclose certain features of construction;

Fig. 5 is a section taken substantially on the line 5—5 of Fig. 3;

Fig. 6 is an enlarged detail view showing certain features of construction to be later described;

Fig. 7 is a section taken substantially on the line 7—7 of Fig. 6; and

Fig. 8 is a section taken substantially on the line 8—8 of Fig. 2.

For the purpose of illustrating my invention I have shown on the drawings so much of a rolling mill as is thought to be necessary to an understanding of my present invention.

Considering first Figs. 1 and 2 which show the mill arranged for the rolling of tires, it will be noted that a shaft 11 is mounted in suitable bearings 12 and 13 and carries a bevel gear 14 which is in constant mesh with a bevel gear 15 fixed upon the end of a horizontally extending shaft 16. The shaft 16 is mounted in suitable bearings 17 and 18 and during each operation of the rolling mill is continuously driven from any suitable source of power (not shown). The shaft 11 carries at its upper end a roll 19 against which the body being rolled is held in rolling. This roll rotates about a fixed axis and when the mill is arranged for the rolling of annular bodies, such as tires for locomotives and car wheels

and the like, a follower roll 21 mounted upon a shaft 22 secured in a support or bearing 23 is provided. The support or bearing 23 is mounted in a carriage generally designated at 24 which rides at its ends in horizontally extending ways 25 formed in the main frame 26 of the mill. These ways extend substantially from the right-hand end of the mill viewing Figs. 1 and 2 to close to the roll 19. The carriage 24 is pulled by pressure toward the left viewing these figures in order that the roll 21 may press firmly against the inner face of the tire or tire blank indicated at 27. This pressure is exerted through any suitable power, in the present instance being supplied through a pull exerted upon a plurality of rods 28.

A pair of rolls 29, one on each side of the roll 19, engage the outer face of the tire as it is rolled. Each of these rolls is carried in a bell crank 31 pivoted at 32 to a part 33 of the main frame. Rods 34 press these bell cranks in the direction of the arrows on Fig. 2 to bring the rolls 29 into pressure engagement with the outer face of the tire, the enlargement of the tire being accompanied by a retraction of the rolls 29 under a substantially uniform pressure.

In the present instance, four rolls 41, 42, 43 and 44 are provided to operate upon the tire approximately diametrically opposite the part engaging the roll 19. Of these rolls 41 and 42 are fixed on inclined shafts or stems 45 and 46 and bear against the side faces of the tire as it is rolled. These two rolls are of frusto conical shape with elements of them engaging the tire in substantial parallelism. In the present instance both the rolls 41 and 42 are positively driven. The lower roll 42 receives its power from the shaft 16. On this shaft a slidable bevel gear 47 is provided which engages a bevel gear 48 on the lower end of the shaft 46. The gear 47 has a bearing 49 affixed to a bearing 50 of the shaft 48 which is part of a movable carriage 51 which, like the carriage 24 of the roll 21, is engaged in its ends in the ways 25 of the horizontal sides 26 of the main frame of the mill. The upper roll 41 of this pair of top and bottom rolls receives its power from a motor 52, electrical in the present instance. The roll 41 and the shaft 45 are also mounted on the carriage 51. The carriage 51 has an upwardly extending arch 53 beneath or through which the shaft 45 extends. This shaft is carried in an elongated bearing 54 which is supported in a bearing support best seen in Fig. 5. Extending out from each side of the bearing and immediate its ends is a pair of trunnions 55 which have a pivotal connection in a slide 56 forming a part of the bearing support. The remainder of this bearing support consists, gen-

erally speaking, of an arch or yoke 57, the lower ends of which are pivoted at 58 on the carriage. The bearing support is swung about its pivotal connection with the carriage by means of a pair of positioning screws 59 which engage trunnions 61 extending out from the sides of the yoke and which are in threaded engagement with sleeves 62 fast in bearings 63 having a trunnion engagement 60 in the carriage frame. Rotative movement is given the sleeves 62 through worms 64 on a horizontally disposed shaft 65 (Fig. 4) which worms engage co-operating worm gears 66. The shaft 65 is provided with a suitable hand-wheel 67 to facilitate the operation of moving the bearing support about its pivot. The slide 56 may be moved toward and from the pivotal connection of the bearing support with the carriage through a shaft 71 carrying worm drives 72 which engage worm gears 73 mounted on the end of screws 74 which turn freely in bearings 75 through the top of the yoke 57 and which have a threaded engagement through the ends 76 of the slide 56. The motor 52 is carried upon a support 77 which is fast to the bearing 54 of the shaft 45 so that movement of the shaft bearing carries with it the motor 52, permitting thereby a permanent gear connection 78 between the motor and shaft 45.

The mill shown on the drawings is readily adjustable to the rolling of tires and other articles having an appreciable range of thickness or lateral width; that is to say, vertical heights when placed in the position shown. To accomplish this the roll 41 is lifted or lowered by swinging the bearing support about its pivotal axis and correspondingly adjusting the bearing in the support through operation of the slide. These two co-operating adjustments serve to maintain the roll 41 in proper vertical alignment with the roll 42, so that they may operate upon opposite ends of a lateral dimension of the blank. A hydraulic pressure cylinder 81 having a link connection at 82 with the forward end of the bearing 54 is provided to exert necessary downward pressure on the roll when the roll is in operation. A positive and adjustable stop 83 is provided upon the upper end of the piston rod 84 of this mechanism to limit downward movement of the roll as the article attains desired size. If desired a second hydraulic cylinder 85 may be provided to counterbalance the weight of the parts.

The two rolls 43 and 44 are carried in a yoke 86 having a pair of bifurcated arms 87. A roll is mounted with its axis in vertical position between the ends of each bifurcated arm and these rolls engage the outer periphery or face of the body being rolled. They are, in the present instance, located one on each side of and close to the

plane of the rolls 41 and 42, so that all four of these rolls work upon a sector of the blank. All four of these rolls extend beyond the edges defined by the top and bottom faces with the outer face of the body upon which they operate. This prevents the formation of a fin or other imperfection. The rolls 43 and 44 in the rolling of tires, perform the dual function of preserving the 10 rotundity and of guiding the constantly enlarging tire properly between the rolls 41 and 42. The yoke 86 is carried at the end of a stem 88 of a piston 89 which takes into a hydraulic cylinder 91 through which suitable pressure may be exerted by the rolls upon the blank. The cylinder 91 is mounted in the carriage 51.

As the tire enlarges the carriage is drawn back in the ways 25 in the main frame, 20 hydraulic cylinders 92 being provided to control this movement. The rolls 19, 43 and 44 are provided with recesses 93 and the roll 19 carries an outwardly extending flange 94 beneath the recess 93 to form a 25 support for the blank. The tire is thus fixedly held in horizontal position during rolling and made to rotate in a smooth although constantly enlarging path of movement. It can be readily measured and 30 the machine stopped when it has arrived at desired dimension.

Figs. 3 and 4 show the same mill with slight changes arranged for the rolling of disk bodies, in the present instance a car wheel being shown. The changes that have 35 been made to change it from one form of mill to the other are the removal of the shaft 22 and the follower roll 21 carried by it, and the substitution of rolls 101 and 102 40 for the rolls 41 and 42 used in the rolling of locomotive tires. The rolls 101 and 102 carry heads 106 for engaging back of the rim 103 of the wheel blank 104. The carriage in these figures is shown as moved 45 closer to the roll 19 by reason of the fact that the car wheel has a less outside diameter than the tire for locomotive wheels shown in Figs. 1 and 2, and also by reason of the fact that it is desirable that the rolls 101 and 102 50 engage back of the rim 103. In the rolling of car wheels the rolls 43 and 44 act as pressure rolls, and the close arrangement of the four rolls 101, 102, 43 and 44 permits the forcing of the flow of metal 55 in the direction desired. The roll 19 is still positively driven and it together with rolls 29 being relatively fixed with respect to the frame, while the carriage 51 carrying the rolls 101, 102, 43 and 44 has a horizontal 60 motion with respect to the frame, enables the operator to control the increase of diameter of the blank and the formation of the flange during operation. He may cause the flange to be formed without appreciable 65 increase of diameter of the wheel blank, or

he may cause the flange to be formed while the diameter is enlarging.

Prior to my invention the rolling mills in use have required the formation of a rough approximation of the flange or a part 70 of the flange upon the blank before it is introduced into the mill. This has required that the dies doing the preliminary work upon the blank determine the outer face or periphery of the blank as well as the side 75 faces. By reason of this fact the range of weight that a blank may have to permit it to be used has been relatively restricted. The fact that the dies engage the outer face has prevented the formation of a blank having 80 excess weight to desired width or lateral thickness without change of dies, and has required the use of presses of tremendous power to bring the blank to the desired configuration with the partly formed flange. It 85 is locked in the dies and the blank cannot be reduced to the desired thickness. Where a mill embodying my invention is used it is not necessary to use dies which confine the outer periphery of the metal. The bloom 90 may be brought to general cylindrical form of approximately the desired weight and placed between dies which will suitably shape and space the side faces without inclosing the outer periphery. The presses 95 may be of much less power. If excess metal be present it results merely in a larger diameter, which, if too much to comply with the specifications, can readily be reduced by machining.

When the apparatus is operating upon car wheels or upon disks of other character the forming or reducing action occurs almost entirely within the relatively small portion of the apparatus included by rolls 101, 102, 105 43 and 44. When thus acting the rolls 29 and 19 merely guide the blank and cause it to retain the form given it by the reducing rolls 101, 102, 43 and 44. By appropriate manipulation of these four rolls during the 110 rolling the sectional rim shape may be changed. The arrangement of the two rolls 43 and 44 close to and at the sides of the pair of rolls 101 and 102 permits the rolls to overlap in their action so that no fins 115 form at the edge of the flange or at the edge of the rim.

It will be manifest that the various parts of the mill may be of strong and durable construction and that the various adjustments may be attained with little delay and expense.

It is thought that the invention and many of its attendant advantages will be understood from the foregoing description, and it 125 will be apparent that various changes may be made in the form, construction and arrangement of the parts without departing from the spirit and scope of the invention defined in the claims or sacrificing any of 130

its material advantages, the form hereinbefore described being merely a preferred embodiment thereof.

I claim:

5. 1. In a rolling mill, means for removably holding a roll for engaging the interior surface of a tire blank, rolls for engaging the rim of either a car wheel blank or of a tire blank, and means for removably holding rolls in coöperative relation with said rim engaging rolls for rolling a car wheel and also alternatively holding rolls in coöperative relation with said interiorly engaging tire blank roll and with said rim engaging rolls to roll a tire. 70
10. 2. In a mill for rolling disk and annular bodies, the combination of a pair of working rolls for determining the thickness of the body being rolled, a roll engaging the outer circumferential face of said body, and means for forcing said roll into working relation with said body in the rolling of disk bodies and for holding it in merely guiding relation in the rolling of annular bodies. 75
15. 3. In a mill for rolling annular and disk bodies, the combination of a pair of working rolls for determining the thickness of the body being rolled, a roll engaging the outer circumferential face of said body, and means 80 for forcing the work into working relation with said roll in the rolling of annular bodies and means for holding said roll in merely guiding relation in the rolling of disk bodies.
20. 35. 4. In a rolling mill, the combination of a plurality of rolls arranged to give desired formation to a car wheel body and arranged to simultaneously operate upon a relatively small sector of said body, and means for 85 positively driving a plurality of said rolls. 90
25. 5. In a rolling mill, the combination of a plurality of reducing rolls arranged to give desired formation to a car wheel body and arranged to simultaneously operate upon a relatively small sector of said body, and driving means arranged to engage said body without said sector. 100
30. 6. In a rolling mill, the combination of a pair of reducing rolls for operating upon the side faces of a disk body and arranged one above the other, and a reducing roll for engaging the outer face of said body, each of said rolls extending over the intersection of the outer face with the side faces. 105
35. 7. In a rolling mill, the combination of a fixed roll and a roll mounted to operate upon the side face of a disk body, a mounting for said last mentioned roll, a driving mechanism carried by said mounting, said mounting and driving mechanism and said roll being movable bodily with respect to said fixed roll. 110
40. 8. In a rolling mill, the combination of a roll adapted to engage a disk or annular body, a shaft on which said roll is mounted, 115 a bearing for said shaft, and a normally inclined bearing support for said bearing in which said bearing is pivoted, and means for moving said bearing longitudinally of said bearing support. 120
45. 9. In a machine for rolling circular blooms, a frame, a carriage sliding thereon, a pair of positively driven rolls mounted on said carriage with their axes inclined toward each other and adapted to bear upon opposite faces of the bloom, in combination with means for shifting said carriage as the bloom increases in diameter under the action of said rolls. 125
50. 10. In a machine for rolling circular blooms, a frame, a carriage sliding thereon, a pair of rolls mounted on said carriage with their axes inclined toward each other and adapted to bear upon opposite faces of the bloom, in combination with coöperating peripheral forming rolls bearing against the periphery of the bloom adjacent the point of its engagement between said inclined rolls and closely adjacent the working area of the latter. 130
55. 11. In a machine for rolling circular blooms, a frame, a carriage sliding thereon, a pair of rolls mounted on said carriage with their axes inclined toward each other and adapted to bear upon opposite faces of the bloom, in combination with coöperating peripheral forming rolls mounted on said carriage and bearing against the periphery of the bloom adjacent the point of its engagement between said inclined rolls and closely adjacent the working area of the latter. 135
60. 12. In a machine for rolling circular blooms, a frame, a carriage sliding thereon, a pair of rolls mounted on said carriage with their axes inclined toward each other and adapted to bear upon opposite faces of the bloom, in combination with coöperating peripheral forming rolls bearing against the periphery of the bloom adjacent but on opposite sides of the point of its engagement between said inclined rolls and closely adjacent the working area of the latter. 140
65. 13. In a machine for rolling circular blooms, a frame, a carriage sliding thereon, a pair of rolls mounted on said carriage with their axes inclined toward each other and adapted to bear upon opposite faces of the bloom, in combination with coöperating peripheral forming rolls mounted on said carriage with freedom of movement relative to the inclined rolls irrespective of the movement of the latter and bearing against the periphery of the bloom adjacent the point of its engagement between said inclined rolls and closely adjacent the working area of the latter. 145
70. 14. In a machine for rolling circular blooms, a frame, a carriage sliding thereon, a pair of rolls mounted on said carriage with 150

their axes inclined toward each other and adapted to bear upon opposite faces of the bloom, in combination with coöperating peripheral forming rolls mounted on said carriage with freedom of movement relative to the inclined rolls irrespective of the movement of the latter and bearing against the periphery of the latter adjacent the point of its engagement between said inclined rolls and closely adjacent the working area of the latter, together with means for forcing said peripheral rolls against the bloom with regulated pressure.

15. In a machine for rolling circular blooms, a frame, a carriage sliding thereon, a pair of rolls mounted on said carriage with their axes inclined toward each other and adapted to bear upon opposite faces of the bloom, in combination with coöperating peripheral forming rolls mounted on said carriage with freedom of movement relative to the inclined rolls irrespective of the movement of the latter and bearing against the periphery of the latter adjacent the point of its engagement between said inclined rolls, and closely adjacent the working area of the latter, together with means for shifting said carriage and moving said peripheral rolls independently of each other.

16. In a machine for rolling circular blooms, a frame, a carriage sliding thereon, a pair of rolls mounted on said carriage with their axes inclined toward each other and adapted to bear upon opposite faces of the bloom, in combination with independent means for driving each of said rolls.

17. In a machine for rolling circular blooms, a sliding roll carriage, a pair of rolls mounted thereon with their axes inclined toward each other and adapted to bear upon opposite faces of the bloom, one of said rolls being held at fixed inclination and the other being movable toward or away from said stationary roll during the working of the bloom together with means for positively driving both of said rolls.

18. In a machine for rolling circular blooms, a sliding roll carriage, a pair of rolls mounted thereon with their axes inclined toward each other and adapted to bear upon opposite faces of the bloom, one of said rolls being held at fixed inclination and the other pivoted on said carriage whereby the latter roll may be approached and retracted from the fixed roll together with means for positively driving both of said rolls.

19. In a machine for rolling circular blooms, a sliding roll carriage, a pair of rolls mounted thereon with their axes inclined toward each other and adapted to bear upon opposite faces of the bloom, one of said rolls being held at fixed inclination, an auxiliary frame pivoted on said carriage,

and a pivotal mounting therein for the second roll.

20. In a machine for rolling circular blooms, a sliding roll carriage, a pair of rolls mounted thereon with their axes inclined toward each other and adapted to bear upon opposite faces of the bloom, one of said rolls being held at fixed inclination, an auxiliary frame pivoted on said carriage, a yoke adjustable in said carriage and a pivotal mounting for said second roll in the yoke.

21. In a machine for rolling circular blooms, a driving shaft, a gear sleeve slideable thereon and having a driving connection therewith, a sliding carriage movable lengthwise of the shaft and engaging said gear sleeve, a pair of rolls mounted in said carriage with their axes inclined toward each other and adapted to bear upon opposite faces of the bloom, one of said rolls having a driving connection with said gear sleeve and being held at fixed inclination, the other roll being movably mounted on the carriage and having means for separating and approaching the same toward the fixed roll together with means for positively driving both of said rolls.

22. In a machine for rolling circular blooms, a driving shaft, a gear sleeve slideable thereon and having a driving connection therewith, a sliding carriage movable lengthwise of the shaft and engaging said gear sleeve, a pair of rolls mounted in said carriage with their axes inclined toward each other and adapted to bear upon opposite faces of the bloom, one of said rolls having a driving connection with said gear sleeve and being held at fixed inclination, the other roll being movably mounted on the carriage and having means for separating and approaching the same toward the fixed roll, together with means for driving said movable roll.

23. In a machine for rolling circular blooms, a pair of rolls having their axes inclined toward each other and adapted to bear upon opposite faces of the bloom, one of said rolls being pivotally mounted to permit of the separation and approach of the rolls, and a driving motor carried by said roll.

24. In a machine for rolling circular blooms, a sliding carriage having a pair of rolls mounted thereon with their axes inclined toward each other, a frame for one of said rolls pivoted on the carriage, an adjustable mounting for the roll in said frame and means for swinging the frame on its pivot, for the purpose described.

25. In a machine for rolling circular blooms, a sliding carriage having a pair of rolls mounted thereon with their axes inclined toward each other, one of said rolls having a fixed inclination, a frame pivoted

- on the carriage and in which the other roll is adjustably mounted to vary its inclination and means for swinging the frame on its pivot to bring said adjustable roll into register with the fixed roll. 5
26. In a machine for rolling circular blooms, a sliding carriage having a pair of rolls mounted therein with their axes inclined toward each other, a swinging roll cradle supported by said carriage and carrying one of said rolls, and a motor mounted on said cradle for driving said roll. 10
27. In a machine for rolling circular blooms, a sliding carriage having a pair of rolls mounted therein with their axes inclined toward each other, a swinging roll cradle supported by said carriage and carrying one of said rolls, and a motor mounted on said cradle for driving said roll, together 15 with means on the carriage for swinging said cradle to lift and lower the roll. 20
28. In a machine for rolling circular blooms, a pair of forming rolls mounted on axes inclined toward each other and having head portions adapted to engage the opposite faces of the bloom in advance of the body portions of the rolls, which bear upon the marginal portion of the bloom, said head portions preventing the inward displacement of the metal by the body portions of the rolls, in combination with peripheral rolls bearing against the bloom adjacent the forming rolls and against which the marginal portion of the bloom is outwardly 30 pressed by the bodies of the inclined rolls together with means for pressing said inclined and peripheral rolls against the bloom simultaneously or in sequence or at independent, variable pressures. 35
29. In a machine for rolling circular blooms, a pair of coöoperating rolls mounted on axes inclined toward each other and adapted to bear upon the opposite faces of the bloom, in combination with forming roll means bearing against the periphery of the bloom closely adjacent the working area of inclined rolls, pressure means for causing the inclined rolls to approach each other to reduce the thickness of the bloom, and independent pressure means for forcing the peripheral roll means against the periphery of the bloom to shape the latter. 40
30. A construction such as specified in claim 29 in which the means for pressing the peripheral roll against the bloom is not only independent of the pressure means for applying the inclined rolls to the bloom, but variable during the operation of the apparatus. 45
31. In a machine for rolling circular blooms, a pair of coöoperating rolls mounted on axes inclined toward each other and adapted to bear upon opposite faces of the bloom, in combination with forming roll means bearing against the periphery of the bloom closely adjacent the working area of the inclined rolls, and means for applying pressure to the inclined rolls and peripheral roll means simultaneously or in sequence, as desired. 50
32. In a machine for rolling circular blooms, a pair of coöoperating rolls mounted on axes inclined toward each other and adapted to bear upon opposite faces of the bloom, in combination with forming roll means bearing against the periphery of the bloom closely adjacent the working area of the inclined rolls, and means for applying pressure to the inclined rolls and peripheral roll means simultaneously or in sequence or at independent, variable pressures, as desired. 55
33. In a rolling mill, having a fixed roll against which an annular or disk body is adapted to engage in rolling the combination of a carriage, a roll carried by said carriage and adapted to operate upon said body, and means for driving said last mentioned roll mounted on said carriage, said carriage being movable with respect to said fixed roll. 60
34. In a rolling mill, the combination of a roll adapted to engage a disk or annular body, a shaft on which said roll is mounted, a bearing for said shaft, a pivotally mounted bearing support for said bearing, and means for shifting said bearing toward and from the pivotal axis of said support. 65
35. In a rolling mill, the combination of a roll adapted to engage a disk or annular body, a shaft on which said roll is mounted, a bearing for said shaft, and a pivotally mounted bearing support in which said bearing is pivoted, both said support and said bearing having a pivotal movement in a vertical plane. 70
36. In a rolling mill for rolling disk bodies, the combination of a pair of reducing rolls for operating upon the side faces of said body and having axes located in the same plane and inclined toward each other, and a pair of reducing rolls operating upon the circumferential face of said body and having axes parallel to the plane of the axes of the first mentioned rolls and located adjacent thereof. 75
37. In a rolling mill for rolling disk bodies, the combination of a pair of reducing rolls for operating upon the side face of said body and having axes located in the same plane and inclined toward each other, and a pair of reducing rolls operating upon the circumferential face of said body and having axes parallel to the plane of the axes of the first mentioned rolls operating upon the circumferential face of the body toward the center of the body. 80
38. In a rolling mill for rolling disk bodies, the combination of a pair of reducing rolls for operating upon the side face of

- said body and having axes located in the same plane and inclined toward each other, and a pair of reducing rolls operating upon the circumferential face of said body and 5 having axes parallel to the plane of the axes of the first mentioned rolls and located adjacent thereof, and independent means for moving said pairs of rolls to change corresponding dimensions of said body.
- 10 39. In a rolling mill, the combination of a group comprising a plurality of reducing rolls located close together to operate upon and give formation to a wheel rim, and a roll located diametrically opposite the center of said plurality of rolls to control the diameter of the wheel during the formation of said rim.
- 15 40. In a rolling mill, the combination of
- a group comprising a plurality of reducing rolls located close together to operate upon 20 and give formation to a wheel rim, a roll located diametrically opposite the center of said plurality of rolls to control the diameter of the wheel during the formation of said rim, and means for producing controlled relatively bodily movement of said plurality of rolls and said roll as the wheel 25 is formed.
- In testimony whereof I have hereunto set my hand in the presence of two subscribing 30 witnesses.

FRANK B. BELL.
